UNITED STATES PATENT OFFICE.

ROBERT DUNCAN CONNOR, OF WITHTINGTON, MANCHESTER, ENGLAND.

WIRE-DRAWING MACHINE.

1,198,111.

Specification of Letters Patent. Patented Sept. 12, 1916.

Application filed October 22, 1915. Serial No. 57,305.

REISSUED

To all whom it may concern:

Be it known that I, ROBERT DUNCAN CONNOR, a subject of the King of Great Britain and Ireland, and resident of Withington, 5 Manchester, England, have invented new and useful Improvements in Wire-Drawing Machines, of which the following is a specification.

This invention relates to apparatus for drawing wire by the continuous method, in which the wire is drawn through a series of dies at one operation.

The object of the invention is to provide a series of drawing blocks, with complementary dies, so constructed and organized that each block exerts on the wire only sufficient pull to draw it through the die immediately preceding it and delivers the wire loosely to the next succeeding die thereby obviating slipping, or pulling, and grinding, on the blocks.

The preferred embodiment of the invention is shown in the accompanying drawings, forming a part of the specification, in view of which disclosure the underlying principle of the invention will be understood by those skilled in the art, irrespective of the concrete structure and arrangement selected for illustrative purposes, 30 wherein—

Figure 1 is a side elevation showing a complete machine constructed according to the invention. Fig. 2 is a side view of the first drawing block and part of the table drawn to a larger scale. Fig. 3 is a cross sectional view through one of the drawing blocks. Fig. 4 is a sectional plan on the line 4, 4 of Fig. 3. Fig. 5 is a side view partly in section showing the drive to the last block on an enlarged scale. Fig. 6 is a diagrammatic plan of the draw bench, showing the train of gear wheels for rotating the drawing blocks. Fig. 7 is a perspective view of a combined die holder and trough to receive the lubricant or other treating material.

Each drawing block comprises the block proper *a*, adapted to receive a sufficient number of convolutions to cause the tractive effort of the block to draw the wire through

the die, and having a reel-like extension adapted to receive the drawn wire. As shown, the latter consists of columns *b* which, with the exception of the final block, support a dome shaped member *c* having a central aperture *d* in line with which depends a central tube *e*, passing centrally through the block and forming a guide for the wire leaving the same.

Means are provided to grip the wire while the initial convolutions are wound on the block and these may consist of a vise having the gripping jaw *f*, manipulated, or controlled, by the stud *g*.

A table or draw bench *h* is formed to receive a series of drawing blocks, corresponding in number to the desired number of reductions, four being shown on the drawings, the first three being formed with a hollow shaft or pillar as above described, while the last block *i* is adapted to receive the finished wire. The driving shaft *j* is journaled in the bench and is provided with fast and loose pulleys *k* and *l* respectively, to receive the driving belt. Upon the shaft *j* is a beveled wheel *m* which meshes with another beveled wheel *n* secured to and adapted to drive the shaft *o* of the block *i*. Another gear wheel *p* on the shaft *o* drives a gear wheel *q* on the preceding block, through an idler wheel *r*, each block being provided with a corresponding gear wheel *q* and receiving motion from the succeeding block through an idler wheel, the gear ratios being such that the peripheral speed of the blocks, increases from the initial block upward as hereinafter explained.

Dies *s* are provided for each block, said dies preferably being positioned by a holder *t* formed in one with or secured to a trough or the like *u* for receiving the usual lubricant or other treating material. Beneath the row of hollow drawing blocks and in line therewith is a shaft *v* mounted in the table *h* and adapted to receive guide pulleys *w*, one of which is located beneath the axis of each of said blocks. These pulleys *w*, in conjunction with a second series of guide pulleys *x*, mounted in brackets *y* on the top of the table, are arranged to guide the wire

from off each drawing block to the next succeeding die, tensioning or braking devices being provided to regulate the supply of wire drawn off the blocks. Such a tensioning device is conveniently formed by an extensible chain band α located in a groove 1 around the dome c , an adjustable spring 2 being provided to govern the tension.

- 10 Draw tongs 3, operated by a cable from the drum 4 are provided for the initial drawing, and handles 5, 5 are conveniently arranged for manipulating the belt fork from either end of the machine.
- 15 The operation of the device is as follows: The undrawn wire is carried on a swift or creel located at the forward end of the machine, said swift or creel preferably being of the tilting type. The end of the wire, 20 after being pointed, is usually led into a soap box through an eccentrically arranged hole in the back thereof, said back being rotated from the driving shaft through the counter shaft 6. The first die is then placed 25 in the last die holder and a short length of the wire drawn therethrough, after which said die is returned to its holder, opposite the first block and the end of the wire secured by the jaw f in the respective vise.
- 30 Upon the machine being started the wire is drawn by the first block until a sufficient number of convolutions are drawn on to it to insure a grip, when the vise is released and the end of the wire passed up under the 35 spring band brake α , over the dome c , down through the tube e and around the respective guide pulleys w , α to the next succeeding die. The latter is preferably placed in the last 40 die holder for ease of manipulation by the draw tongs, but upon the release of the draw tongs, the die is removed to its respective holder and the cycle of operations repeated as with the first draw block, each succeeding draw block being started in a similar manner until the last is reached, upon which the 45 drawn wire gathers, as will be apparent from the drawings.

When all the drawing blocks are in operation the wire is drawn in a continuous manner through the successive dies, and the gear ratios of the drawing blocks are normally such, that the peripheral speed of each succeeding block is greater than that of the preceding block, by an amount rather less than 50 is sufficient to take off the wire from said preceding block, due allowance being made for the elongation of the same, so that a gradual accumulation of the wire takes place on the respective blocks, that portion 55 of the wire between each block and the succeeding die being free from tension, and thus allowing of its being drawn forward by the succeeding block without friction.

As the supply of wire is exhausted at the feeding end, there is ample time for the machine minder to refill the swift or creel and prepare for the next operation before the wire is exhausted from all the drums. If desired, a trough 7 may be suspended below the guide pulleys w containing suitable 70 treating material when it is desired to use the wet process of drawing.

It will be observed that no slipping, pulling or grinding takes place on the drawing blocks, consequently no loss of driving 75 power is occasioned or undue stresses or strains imparted to the wire, thereby permitting the machine to be run at relatively high speeds, and allowing the wire to be drawn down more than heretofore without 80 intermediate annealing. Further, by reason of the wire being caused to accumulate between each pair of dies, it is cooled before reaching the next die, the rotation of the block materially assisting in the effect.

85 What I claim is:

1. Apparatus for drawing wire by the continuous method comprising, in combination, a series of drawing blocks and a series 90 of dies, together with guiding means, each drawing block being adapted to draw the wire through its die and accumulate the drawn wire thereon, until guided to the next block, the speed ratios of the blocks being such as to maintain a succession of loose 95 wire upon each block substantially as described.

2. Apparatus for drawing wire through a series of reductions continuously in one operation, comprising, a series of drawing 100 blocks, complemental dies, means for rotating all the blocks at different peripheral speeds, the increase in the peripheral speed of each succeeding block being less than that required to take up the wire wound on the 105 preceding block, and means on each block for controlling the drawing off of the wire, substantially as described.

3. In apparatus for drawing wire continuously through a succession of dies, a series 110 of dies, a series of hollow drawing blocks each adapted to receive and accumulate the drawn wire and being provided with tensioning means through which said wire is led to the next succeeding die, substantially 115 as described.

4. In apparatus for drawing wire by the continuous method, a series of vertically arranged hollow drawing blocks each provided with a superstructure having a hollow dome head and a spring band brake, a final drawing block provided with a storing reel, means for rotating all the blocks at different peripheral speeds, and means for guiding the wire, substantially as described.

120 5. In apparatus for drawing wire by the

continuous method, a series of vertically arranged hollow drawing blocks each provided with a superstructure having a hollow dome head and a spring band brake, a final drawing block provided with a storing reel, means for rotating all the blocks at different peripheral speeds, means for guiding the wire and means for containing and holding

treating material in proximity to the wire, substantially as described.

In witness whereof I have hereunto set my hand in the presence of two witnesses.

ROBERT DUNCAN CONNOR.
